(57) **CLAIM**

An ornamental design for a soft hand restraint for transporting prisoners, as shown and described.

DESCRIPTION

FIG. 1 is a front perspective view showing the design of a soft hand restraint for transporting showing wrist restraints in closed position and the handcuff retaining strap in the open position.

FIG. 2 is rear perspective view of the soft hand restraint for transporting prisoners showing the wrist restraints in closed position and the handcuff retaining strap in the open position.

FIG. 3 is a rear perspective view of the soft hand restraint for transporting prisoners, showing the wrist restraints in closed position and the handcuff retaining strap in the closed position.

FIG. 4 is a left side elevation view of the soft hand restraint for transporting prisoners; the right side being substantially similar, showing wrist restraints and the handcuff retaining strap in the open position.

FIG. 5 is a bottom plan view of the soft hand restraint for transporting prisoners, wherein the wrist restraints and the handcuff retaining strap are shown in the closed position.

FIG. 6 is a top plan view of the soft hand restraint for transporting prisoners, wherein the wrist restraints and the handcuff retaining strap are shown in the closed position.

FIG. 7 is a front perspective view showing the soft hand restraint for transporting prisoners showing the handcuff retaining strap and wrist restraints in the closed position.

FIG. 8 is a front perspective view showing the design of another embodiment of the soft hand restraint for transporting prisoners having a seat belt restraint slot that incorporates the handcuff retaining strap located in the proximity of the top edge, showing the wrist restraints and the handcuff retaining strap in the closed position, wherein a plurality of D-Rings are affixed to the left and right mid-front, and the bottom, left and right edges, beyond this aspect alone, all other elements and aspects of the design being substantially similar; and,

FIG. 9 is a front perspective view showing the design of another embodiment of the soft hand restraint for transporting prisoners having a seat belt restraint slot that incorporates the handcuff retaining strap located in the proximity of the top edge, showing the wrist restraints and the handcuff retaining strap in the closed position, wherein a plurality of D-Rings are affixed to the left and right mid-front, and the bottom, left and right edges, showing binders (retaining straps) engaged in the D-Rings about the edges, beyond this aspect alone, all other elements and aspects of the design being substantially similar.
